ENGINE STARTER

William H. Weimer, North Prairie, Wis., assignor
to Air Diesel Engine Corporation, Jackson,
Mich., a corporation of Delaware

Application April 8, 1946, Serial No. 660,530

6 Claims. (Cl. 185—37)

1

The present invention relates to engine starters and more particularly to those of the spring motor type.

An object of the invention is to provide an engine starter of simple, durable and inexpensive construction capable of ready application to an engine and particularly suitable for small internal combustion engines of either the compression-ignition or spark-ignition type.

Another object is to provide an engine starter which is so arranged as to permit safe and easy tripping of the spring motor and to avoid damage to the parts by impact.

A further object is to provide a starter having simple but effective means for releasably coupling the spring motor to the engine shaft.

The invention further consists in the several features hereinafter described and claimed.

In the accompanying drawings,

Fig. 1 is a longitudinal sectional elevational view of an engine starter embodying the invention;

Fig. 2 is a detail sectional view taken generally on the line 2—2 of Fig. 1;

Fig. 3 is a detail sectional view taken generally on the line 3—3 of Fig. 1;

Fig. 4 is a detail view of the inner end of the motor spring;

Fig. 5 is an end view of the starter, parts being broken away and parts being shown in section;

Fig. 6 is a detail sectional view taken generally on the line 6—6 of Fig. 5, parts being omitted, and

Fig. 7 is a detail sectional view taken on the line 7—7 of Fig. 5.

In the drawings, 10 designates the crank-shaft of an internal combustion engine, and 11 designates a fly-wheel secured to the shaft, the fly-wheel having a circular recess 12 the peripheral wall of which is defined by a fly-wheel rim 13. The engine may be of any suitable construction and is here shown to include a frame base 14 and a fly-wheel housing 15. The end of the crank-shaft has a coaxial extension member 16 rigidly secured thereon in any suitable manner, as by a screw-threaded connection, the extension member having a cylindrical outer end portion 17 and an enlarged inner end portion with ratchet teeth 18. A bushed coupling sleeve 19 is rotatably and slidably mounted on the cylindrical portion 17 of the shaft extension member and has an annular flange 20 at its inner end. Pawls or dogs 21 are pivotally mounted on the flange 20 on axes parallel to the crank-shaft axis and are urged inwardly against the

ratchet teeth 18 by leaf springs 22, Fig. 2, secured to the flange, these springs also resisting centrifugal force on the pawls. The inward travel of the pawls is limited by an annular stop bead 23 on the sleeve, the outer diameter of the stop bead being slightly larger than the root diameter of the ratchet teeth. The sleeve is outwardly shiftable in an axial direction, as hereinafter described, to effect complete release of the pawls from the ratchet teeth, so as to avoid pawl contact when the engine is running, and the stop bead 23 facilitates reentry of the pawls onto the ratchet teeth for a subsequent starting operation.

A spirally coiled leaf spring 24 extends into the fly-wheel recess 12 and has an inner end secured to the sleeve 19, as by a button 25 on the sleeve engaging in a keyhole slot 26 in the spring, Fig. 4, the spring being of a size or capacity to suit the starting requirements of the engine. The outer end of the spring has a loop or eye 27 anchored on a stationary pin 28 secured to the lower portion of a stationary frame member 29. The frame member has side arms 30 detachably fastened to the engine base 14 and has a cylindrical portion 31 which extends about the spring concentrically of the fly-wheel 13 to limit the expansion of the spring so that the spring will not rub on the inner wall of the fly-wheel rim. A flat peripheral flange 32 formed on the cylindrical portion 31 bears against the fly-wheel housing 15. The frame has a flat annular wall portion 33 axially confining the outer edges of the spring convolutions except for a few of the inner convolutions which are free to move axially when the sleeve 19 is shifted outwardly. The frame also has an apertured hood portion 34 at the projected axis of the engine shaft, this portion having a central opening 35 to admit a spring-winding shaft 36 such as a removable hand crank. The winding shaft has a suitable releasable driving connection with the sleeve 19 as by means of a cross-pin 37 on the winding shaft engageable in notches 38 in the sleeve.

The outer end of the sleeve 19 extends in the hood portion 34 and is shouldered to receive a flange ring 39 which is welded or otherwise rigidly secured to the sleeve, there being an elongated notch or recess 40, Fig. 3, in the periphery of the ring to form end stop shoulders 41. The inner face of the flange ring carries a flat annular wear member 42. A ratchet disk 43 is journaled on the outer end of the sleeve in close proximity to the flange ring and is axially confined between the flange ring and a spring re-

taining ring 44 on the sleeve. The ratchet disk 43 carries a laterally projecting pin 45 which is movable in the notch 40 of the flange ring 39 and is engageable with the stop shoulders 41. A pawl or dog 46 is pivoted on a pin 47 carried on the frame member 29 and is engageable with the teeth of the ratchet disk 43 to prevent unwinding of the spring 24, the pawl being held in operative position by a coiled tension spring 48 which engages an arm 49 of the pawl. A trip member 50 is pivoted on a pin 51 carried on the frame and has an arm 52 engageable with the arm 49 of the pawl 46 for releasing the pawl from the toothed ratchet disk 43. The trip member is operated by a foot-operated control arm 53 which is pivotally carried on a vertical pin 54 on the trip member and has forked portions 55 engageable with the wear member 42 of the flange ring and with the ratchet disk 43 to move the sleeve member 19 axially on the shaft extension 17. A detent spring 56 secured to the wall 33 of the frame member 29 is engageable with the arm 53 to hold the arm in either of its laterally shifted positions. In order to prevent tripping of the pawl 46 when the winding shaft 36 is engaged with the sleeve, the trip member 50 is provided with a finger 57 movable transversely in the path of this shaft, the shaft when present forming a stop to prevent actuation of the trip member. The stop finger is preferably carried on the trip member, as shown, but as an alternative, a similar finger could be carried on the pawl 46.

When the engine is to be started, the sleeve 19 is pushed inwardly by the forked control arm 53, placing the pawls 21 in cooperation with the ratchet teeth 18. In some instances the spring 24 may be relied on to effect the inward shifting of the sleeve. The winding shaft 36 is then engaged with the sleeve and is manually rotated counterclockwise as viewed in Fig. 5, causing the spring 24 to be wound up, the pawls 21 sliding over the ratchet teeth 18, and the toothed ratchet disk 43 being rotated by the flange ring 39 and pin 45 and sliding over the stop pawl 46 which prevents unwinding of the spring when the winding force is removed. The stop finger 57 prevents accidental tripping of the stop pawl while the winding shaft is engaged, so as to avoid possible injury to the operator. Upon release of the winding force, the sleeve 19 will turn in the opposite direction through a part of a revolution until the pawls 21 engage the shoulders of the teeth 18, this being permitted by the elongated notch 40 in the flange ring 39. This relation avoids any impact damage to the pawls 21 and cooperating ratchet teeth when the spring unwinds after the tripping operation. The winding shaft or crank handle 36 is then withdrawn, and tripping of the pawl 46 is effected by pushing the arm 53 downwardly to the broken line position of Fig. 5, whereupon the unwinding spring 24 spins the engine shaft 10 rapidly through several revolutions to start the engine. After the engine starts, the arm 53 is swung laterally to shift the sleeve 19 outwardly, so as to completely release the pawls 21 from the ratchet teeth 18, the arm 53 being held in its displaced position by the detent spring 56. A few of the inner convolutions of the spring shift outwardly with the sleeve, while the remaining convolutions remain in position.

The starter is simple in construction and reliable in operation and permits easy hand starting of engines, such as diesel engines, which are

difficult or impossible to start by direct hand cranking. The entire starter, with the exception of the shaft extension 16, forms an assembly which can readily be applied as a unit to the engine by bolting the two frame arms 30 to the engine base. Removal of the assembly from the engine is equally simple, the coupling sleeve 19 being slidable from the shaft extension and being then supported by the winding spring.

What I claim as new and desire to secure by Letters Patent is:

1. In an engine starter, a stationary frame, an engine shaft, a coupling sleeve rotatable and axially slidable on said shaft, a spirally coiled spring having its inner end secured to said sleeve, means for anchoring the outer end of said spring to said frame, said sleeve adapted to be rotated for winding the spring, releasable holding means for preventing unwinding of the spring, one-way driving means for connecting said sleeve to said engine shaft to effect rotation of said shaft by the unwinding of said spring, said driving means including a ratchet on said shaft and a pawl on said sleeve, means for releasing said holding means to permit unwinding of said spring, and means for axially shifting said sleeve to effect release of said pawl from said ratchet when the engine shaft is running.

2. In an engine starter, a stationary frame, an engine shaft, a spring motor having a windable spring and a rotatable and axially shiftable coupling member connected to an end of said spring, the other end of said spring being anchored on said stationary frame, means for supporting said coupling member coaxially of said engine shaft, releasable holding means for preventing unwinding of said spring, one-way pawl-and-ratchet driving means for connecting said coupling member to said engine shaft to effect rotation of said shaft by the unwinding of said spring, means for releasing said holding means to permit unwinding of the spring, and means for axially shifting said coupling member to effect release of said driving means when the engine is running.

3. In an engine starter, an engine shaft, a coupling member rotatably carried by said shaft and adapted to be rotated by a winding member, a spirally coiled spring having its inner end secured to said coupling member, means for anchoring the outer end of said spring, releasable ratchet means for preventing unwinding of the spring, ratchet means for connecting said coupling member to said engine shaft for effecting driving of said shaft by the unwinding of the spring when said first-named ratchet means is released, means for releasing said first-named ratchet means to permit unwinding of the spring, and means for releasing said shaft-driving ratchet means out of ratchet contact when the engine is running, the releasing means for said first-named ratchet means and said shaft-driving ratchet means including a manually operable member common to both of said releasing means.

4. In an engine starter, an engine shaft member, a rotatable coupling member coaxial with said shaft member, a spirally coiled spring having its inner end secured to said coupling member, means for anchoring the outer end of said spring, ratchet teeth on one of said members, a pawl on the other member engageable with said teeth to drive said shaft upon the unwinding of the spring, said coupling member adapted to be rotated for winding the spring, a toothed ratchet member rotatable on said coupling member through a limited angle to provide for angular

play between said ratchet member and coupling member, said ratchet member and coupling member having cooperating stop means to limit said angular play and to provide a driving connection, a releasable stop pawl engageable with said ratchet member to prevent unwinding of the spring when the winding force is removed, said angular play between said ratchet member and coupling member permitting engagement of said driving pawl with one of the associated ratchet teeth upon removal of the winding force, and means for releasing said stop pawl from said ratchet member to permit unwinding of the spring.

5. In an engine starter, an engine shaft, a fly-wheel on said shaft having a circular concentric recess, a stationary frame member having a recess confronting said fly-wheel recess, a spirally coiled spring extending into both recesses and peripherally confined by said frame member recess, the outer end of said spring being anchored on said stationary frame member, a coupling member rotatably mounted on said engine shaft, the inner end of said spring being secured to said coupling member, said coupling member being adapted to be rotated to wind said spring, a one-way driving connection between said coupling member and shaft for driving said shaft, releasable holding means for said coupling member to prevent unwinding of the spring when the winding force is removed, and means for releasing said holding means to permit unwinding of the spring.

6. In an engine starter, an engine shaft, a fly-wheel on said shaft having a central recess, a rotatable coupling member coaxial with said shaft, means for supporting said coupling member, a spirally coiled spring extending into said fly-wheel recess and having its inner end secured to said coupling member, a stationary frame member enclosing the outer side of said spring and confining the expansion of said spring, means for anchoring the outer end of said spring on said stationary frame member, said coupling member being adapted to be rotated by a winding member to wind the spring, and driving means releasably connecting said coupling member and shaft rotating said shaft.

WILLIAM H. WEIMER

It is hereby certified that error appears in the printed specification of the above numbered patent requiring correction as follows:

Column 6, line 14, after "shaft" insert *for*;
and that the said Letters Patent should be read as corrected above, so that the same may conform to the record of the case in the Patent Office.

Signed and sealed this 11th day of December, A. D. 1951.
